US00D759670S

(12) **United States Design Patent**
Lee et al.

(10) **Patent No.:** US D759,670 S
(45) **Date of Patent:** ** Jun. 21, 2016

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventors: **Bo La Lee**, Seoul (KR); **Woo-Seok
Hwang**, Seoul (KR); **Yong Hwan
Kwon**, Seongnam-si (KR)

(73) Assignee: **SAMSUNG ELECTRONICS CO.,
LTD. (KR)**

(**) Term: **14 Years**

(21) Appl. No.: **29/503,505**

(22) Filed: **Sep. 26, 2014**

(30) **Foreign Application Priority Data**

Mar. 31, 2014 (KR) 30-2014-0016057

(51) **LOC (10) Cl.** **14-04**

(52) **U.S. Cl.**

USPC **D14/485**; D14/486

(58) **Field of Classification Search**

USPC D14/485-495; D18/24-32; D20/10-40
CPC G06F 3/048-3/04897; G06F 17/24;
G06F 2203/04803-2203/05; H04N 1/0044;
H04N 1/00196; H04N 21/47217; G06T
2200/24; G11B 27/10; H04M 1/72561

(57) **CLAIM**

We claim, the ornamental design for a display screen or portion thereof with graphical user interface, as shown and described.

DESCRIPTION

The sole FIGURE is a front view of a display screen or portion thereof with graphical user interface showing our new design. The broken lines illustrate a display screen or portion thereof, and form no part of the claimed design.
